PROCESS FOR FABRICATING METAL BOBBINS FOR AUTOMATIC LOOMS

Helmut Junghans, Schramberg-Sulgen,
GermanyApplication May 17, 1933, Serial No. 671,572
In Germany May 17, 1932

7 Claims. (Cl. 29—170)

The present invention relates to an improvement in process for fabricating metal bobbins for automatic looms. Metallic bobbins as hitherto employed for the purpose are usually formed with 5 an enlarged butt or heel end equipped with steel rings for the fixation of the bobbin in the shuttle.

As the bobbins are frequently changed and accordingly struck from and reattached to the shuttles, thus causing each time the holding springs 10 of the shuttle to slide over the rings of the bobbin, the latter are subject to excessive wear so that the idea of using steel rings with a protective coating for the prevention of corrosion, when or if the bobbin has been dipped into water or come in 15 contact with steam, is not practical, since such coating will soon be worn away due to the friction of the springs. Consequently it would be more reasonable to use rings of incorrodible steel, which however are difficult to draw or even cannot 20 be drawn at all and possess very little elasticity so that it will be impossible to mount such rings in the usual way on the enlarged heel end of the bobbin, owing to lack of resiliency, or to forcibly cause the same to engage annular grooves in the 25 heel end.

According to the present invention this disadvantage is overcome by mounting such closed rings with flat sides and of relatively large radial width on the butt or heel end of the bobbin and 30 securing the same in place by means of annular beads or the like either formed integral on and with the enlarged heel end by jolting or pressing etc. or formed integral on the outer surface of a ferrule adapted to be rigidly connected with the 35 head or heel end of the bobbin.

As the rings required for this purpose cannot be drawn but must be made by punching, another important advantage may be realized by the present invention. According to the latter the 40 rings shall have a predetermined external diameter and be of sufficient width, in radial direction, to exactly fit immediately about the heel end of the bobbin. The conical shank of the bobbin is of small diameter compared to the 45 external diameter of the rings which required the head or heel end of the bobbin to be enlarged correspondingly in manufacture when the rings are of small radial width, or if the bobbin is made from a tubular blank of the same diameter as 50 that of the head, a considerable reduction to the smaller diameter of the shank portion of the bobbin is necessary. Considerable difficulties are encountered either way, which, however, are at once avoided by the present invention.

Another object of my invention resides in the 55

provision of improved means for the detachable connection of the heel end of the bobbin with the spindle for the purpose of refitting a spent bobbin.

I will now start to describe my invention more 5 in detail in connection with the embodiments thereof illustrated on the accompanying drawing, it being intended and understood that the invention is illustrated by, but not limited to the embodiments thereof so illustrated and described. 10

In the drawing six embodiments of the present invention are shown in sectional views, wherein the general shape of the bobbin may be the same throughout, whereas the features or means for fixing the rings on the same and for ascertain- 15 ing and securing the correct distance between adjacent rings will vary in the several embodiments shown.

Figure 1 is a sectional elevation of a bobbin embodying the invention.

Figs. 2, 3 and 4 are similar views, but omitting 20 part of the shank, of modified constructions.

Fig. 5 is a cross-section of a modified form of ring.

Fig. 6 is a sectional elevation of a further modification, and

Fig. 7 is a sectional elevation, omitting part of the shank, of a bobbin having a guiding sleeve fitted inside the bead.

Figure 1 shows a somewhat conical bobbin 30 with a conical shank A merging into a head B of not greatly larger diameter, on which four rings a are mounted to snugly fit in shallow annular grooves produced by pressing the wall of the head from within to form parallel external beads 35 b between which, the said rings are rigidly fixed on the head at the proper lateral distance apart from each other. The shank A merges into the head B through an intermediate conical portion d.

Figure 2 illustrates a modification of the means employed for fixing the rings on the head. It will be seen that in this figure, as also in the Figures 3, 4, 6 and 7, only the head of the bobbin 45 is shown, the shank portion being broken off for convenience' sake, because the same may be of any conventional or known configuration.

In Figure 2 the intermediate beads b of Figure 1 are omitted and spacing rings c of smaller external diameter are interposed between adjacent rings a, and the two end rings a are anchored by beads so that the entire set of four rings a and three spacing rings c will be firmly connected with and rigidly secured on the head of the 50 bobbin.

In Figure 3 the rings *a* are fitted and secured to the head in a manner similar to that shown in Figure 1, the sole difference therebetween residing in the particular way of producing the beads *b* by jolting instead of internal pressure. After the four rings *a* have been fitted on the head and secured in place by the jolting operation, three spacing rings not shown each consisting or adapted to be composed of two semicircular halves, are inserted into the three spaces between the four rings *a* whereupon, by way of a pressing operation, the ribs *b*, that is the spaces between the rings *a*, are equalized to conform to the width of the said spacing rings.

15 Figure 4 illustrates a modification wherein the four rings *a* (shown in Figures 1 to 3) and the spacing rings *c* (shown in Figure 2) form an integral unit in the shape of a ferrule or cross-channelled sleeve which may be made by turning 20 on a lathe or by casting and which may be provided with circular grooves on the inside surface adapted to engage with corresponding annular ribs *e* of the head for fixing purposes as shown.

The rings *a* are substantially flat on both sides 25 and of great radial width compared with the wire rings heretofore used, but the sides of the rings *a* may be reduced at the inner periphery, as shown in Figure 5.

In the modification shown in Figure 6 four 30 rings *a* are mounted on the enlarged head *B* of the bobbin and secured in place in the same way as described hereinbefore with reference to Figure 3, each ring *a* being embedded between two adjacent annular beads *b* preferably produced by 35 a jolting operation or a compressing stroke. The lower end of the head is shaped to form a cone *g* the base end *b'* of which has a diameter only slightly less than that of the contiguous ring *a*.

It will be readily understood from the foregoing description and the drawing that a bobbin 40 of the construction shown in Fig. 6 can be easily inserted into the resilient holder of a spindle, since the conical part *g* of the head will press apart the holding springs during the inserting 45 operation and the free ends of the springs will engage, at the end of said operation, in the space between any two adjacent rings *a*.

Just as the annular ribs *b* may be produced 50 successively by jolting after the rings *a* have been individually mounted on the tube head, also the end portion *g* of the head may be shaped into the desired conical form after the last ring *a* has been mounted and secured in place, the upper or base end *b'* of the cone *g* serving to secure the 55 lowermost ring *a* in place.

In the modification illustrated in Figure 7 a metallic sleeve *i* is inserted in the head or heel end of the bobbin so as to snugly fit therein and to project with its reduced inner end *k* into the 60 stem or shank of the bobbin. The inside diameter of the inner end *k* of the sleeve is only a little larger than the diameter of the spindle at this place so as to form a reliable guiding means in the operation of placing the spent bobbin on the 65 spindle. The properly inserted sleeve *i* is secured in place preferably by means of the last bead *b'* in the rear or at the bottom of the lowermost ring *a* which it engages by means of a lip *l*.

In order to give a full understanding of the 70 embodiments shown in Figures 6 and 7, I will explain the same hereinafter a little more in detail.

The spent bobbins removed from the shuttles are placed on the spindles of a spooling machine or the like in order to be filled again, as usual in 75 the weaving art. Now for the purpose of facili-

tating the operation of placing the bobbins on the spindles, according to the present invention, the bead *b'* provided for securing the lowermost ring *a* in place, is made to project a little beyond the tops of the other beads *a* so as to come near a point or the circle where the roundness of the outer face of the lowermost ring begins, while the free extremity of the head is shaped to form a cone *g*, adapted to afford a suitable ramp or slope for the holding springs of the spindle to be 10 guided thereon when the bobbin is placed on the spindle for the refilling purpose.

Bobbins having a conical heel end or head are in themselves known in the art. It is, however, a chief object of the present invention to provide 15 bobbins whereof the body is made of a single piece of metal and which may be manufactured by wholesale in a ready, expedient manner, and with the advantage that by the operation of forming the conical slope *g* the lowermost ring *a* will at 20 the same time be secured in place by such operation.

Metallic bobbins as hitherto used in connection with automatic weft-replenishing looms are usually made of very thin sheet metal and, therefore, have a correspondingly large inside width or diameter which is far in excess of the diameter of the spindle on which the spent bobbin is placed for the refilling purpose. As in the operation of placing a bobbin onto and about the spindle the holding springs of the latter come in contact with the heel end or head of the bobbin, while a comparatively large free space or clearance still exists between the spindle and the inner surface of the bobbin, a certain difficulty prevails in centering the latter properly respecting the said springs and the spindle head or guiding the same accurately so as to thereby avoid all trouble and friction.

As hereinbefore mentioned it is an object of the 40 present invention to provide improved means for facilitating the centering and attaching of the bobbin on the spindle, by preventing the inner grooves of the bobbin head corresponding to the external beads, when once the bobbin is really 45 moved onto the spindle while in excessively slanting position, from collision with the top end of the spindle, and further by providing the best possible guidance which, at or towards the end of the attaching operation, will prevent the bobbin from 50 being laterally displaced by the holding springs of the spindle adapted to grip the head of the bobbin, so as to maintain a substantially coaxial relationship as regards the bobbin and the spindle.

To this end the present invention provides 55 preferably a sleeve adapted to snugly fit in the head of the bobbin so as to overlie the inner grooves of the head and project with its inner reduced end into the slightly conical shank of the bobbin. It will be seen that the reduced end 60 of the sleeve constitutes a reliable guiding means in the operation of positioning the bobbin on and about the spindle, the sleeve being secured in place by the lowermost rib of the bobbin head as hereinbefore described with reference to Figure 6. 65 Obviously the guiding means realized by the provision of the said sleeve, will be effective even at a time when the holding springs have not come in contact as yet with the head of the bobbin. In the subsequent further movement of the bobbin 70 to its final or working position on the spindle the former is properly guided and centered so as to occupy its place on the enlarged portion or head of the spindle, in correct position, that is, coaxially with the spindle.

Usually there is a conical portion d between the head and the tubular stem or shank of the bobbin and the sleeve is correspondingly shaped to form an analogous intermediate conical portion 5 i adapted to fit snugly in the former. Further the reduced inner end of the sleeve may be provided with an external annular rim k' which will assist in centering the sleeve with the aid of said intermediate conical portion, when the sleeve is inserted or forced home into the head of the 10 bobbin.

I have herein described and shown several practical embodiments of my present improvements, but it will be apparent that the same are 15 susceptible of embodiment in various other alternative forms and I, therefore, reserve the privilege of resorting to all such legitimate changes as may be fairly embodied within the spirit and scope of the invention claimed.

20 What I claim is:—

1. A process for fabricating metal bobbins for automatic looms, comprising forming a hollow blank having a shank and a smooth walled head of slightly greater diameter than the shank, forming a bead in the wall of said head at the end 25 remote from the shank, placing on said head against the bead a closed ring of corrosion resisting material, forming a second bead in the wall of said head in front of the ring, placing a second 30 and similar ring on said head against the last made bead, forming a third bead in the wall of the head in front of the second ring, and so on until the desired number of rings spaced axially by beads is fixed on the head, said beads being 35 formed in the wall of the head by a compressing stroke.

2. A process for fabricating metal bobbins for automatic looms, comprising forming a hollow blank having a shank and a smooth walled head of slightly greater diameter than the shank, forming a bead in the wall of said head at the end 40 remote from the shank, placing on said head against the bead a closed flat sided ring of external diameter corresponding to the full bobbin 45 head diameter, forming a second bead in the wall of said head in front of the ring, placing a second and similar ring on said head against the last made bead, forming a third bead in the wall of the head in front of the second ring, and so on 50 until the desired number of rings spaced axially by beads is fixed on the head, said beads being formed in the wall of the head by a compressing stroke.

3. A process for fabricating metal bobbins for 55 automatic looms, comprising forming a hollow blank having a shank and a smooth walled head of slightly greater diameter than the shank, forming a bead in the wall of said head at the end remote from the shank, placing on said head against the bead a closed ring of corrosion resisting material, placing a spacing ring of corrosion resisting material and of lesser external diameter than the first mentioned ring on said head adjacent 60 said first-mentioned ring, and placing further

rings similar to said first mentioned ring on said head adjacent the spacing ring, said further rings alternating with spacing rings, and forming a further bead in said head to retain said alternating rings thereon.

4. A process according to claim 3, in which the beads are formed in the wall of the head by a compressing stroke.

5. A process for fabricating metal bobbins for automatic looms, comprising forming a hollow 10 blank having a shank and a smooth walled head of slightly greater diameter than the shank, forming a bead in the wall of said head at the end remote from the shank, placing on said head against the bead a closed ring of corrosion resisting 15 material, forming a second bead in the wall of said head in front of the ring, placing a second and similar ring on said head against the last made bead, forming a third bead in the wall of the head in front of the second ring, and so on until 20 the desired number of rings spaced axially by beads is fixed on the head, the first formed bead being carried out farther toward the periphery of the adjacent ring than the other beads and is then tapered conically towards the end of the 25 head.

6. A process for fabricating metal bobbins for automatic looms, comprising forming a hollow blank having a shank and a smooth walled head of slightly greater diameter than the shank, forming a bead in the wall of said head at the end remote from the shank, placing on said head against the bead a closed ring of corrosion resisting 30 material, forming a second bead in the wall of said head in front of the ring, placing a second and similar ring on said head against the last made bead, forming a third bead in the wall of the head in front of the second ring, and so on until the desired number of rings spaced axially by beads is fixed on the head, said beads being 35 formed by mechanical pressure exerted outwardly against the internal wall of said head and adjacent beads being spaced apart a distance equal to the width of the ring therebetween.

7. A process for fabricating metal bobbins for 40 automatic looms, comprising forming a hollow blank having a shank and a smooth walled head of slightly greater diameter than the shank, forming a bead in the wall of said head at the end remote from the shank, placing on said head against the bead a closed flat sided ring of 45 external diameter corresponding to the full bobbin head diameter, forming a second bead in the wall of said head in front of the ring, placing a second and similar ring on said head against the last made bead, forming a third bead in the wall of the head in front of the second ring, and so on until the desired number of rings spaced axially by beads is fixed on the head, said beads being 50 formed by mechanical pressure exerted outwardly against the internal wall of said head and adjacent beads being spaced apart a distance equal to the width of the ring therebetween.

HELMUT JUNGHANS.
